GARMENT BLOCKING AND FORMING APPARATUS

Owen V. Brown and Jefferson D. Brown, Fort Worth, Tex., assignors, by direct and mesne assignments, of twenty-five per cent to Travis H. Small, and twenty-five per cent to J. A. Lovell, both of Fort Worth, Tex.

Application March 21, 1938, Serial No. 197,117

8 Claims. (Cl. 223—68)

This invention relates to laundry and dry cleaning equipment for wearing apparel and it has particular reference to apparatus for blocking and forming garments, such as women's gowns and fancy dresses, and its principal object resides in the provision of an adjustable frame structure generally conforming in outline to the human form and designed for expansion and contraction uniformly altering its contour to attain the desired size and shape.

Another object of the invention resides in the provision of a device of the character described especially adapted to use in cleaning establishments for retaining garments in their original size and shape while drying, particularly when such garments have been washed rather than dry cleaned, and eliminating much of the necessity for pressing the article afterward, it being necessary only, in most instances, to merely "touch up" any trim, or the like.

Yet another object of the invention is manifest in the provision of a device embodying few operative parts and presenting a simple, inexpensive structure which affords an economical medium through which cleaners can properly perform the operations usually attendant upon the cleaning and pressing of delicate fabrics without injury thereto and maintain the size and shape of the garments.

Broadly, the invention seeks to comprehend the provision of a device highly useful in the art of cleaning, easily manipulated and providing means enabling cleaners operating small and modest plants to offer a service to the public equal in every respect to that afforded by larger establishments, and such device may find favor in the home.

While the foregoing objects are paramount, other and lesser objects will become manifest as the description proceeds taken in connection with the appended drawing wherein:

Figure 1 is a front elevational view of the invention illustrating, in dotted lines, a variation in its contour.

Figure 2 is a fragmentary cross-sectional illustration of one of the adjustments of the invention.

Figure 3 is a fragmentary side elevational view of the central stay supporting the framework of the device.

Figure 4 is a fragmentary cross-sectional illustration of one of the adjustable retaining members slidably engaging the flexible frame, and

Figure 5 is a lateral cross-sectional illustration of the stay member.

Accordingly, therefore, the invention consists

primarily of a main supporting or body member 1, preferably of wood, and comprising two sections each having a longitudinal groove 2 in their opposing faces. Thus, when the two sections of the member 1 are assembled and a strip of sheet metal 3 placed therebetween, a pair of longitudinal passages 4 and 5 extending entirely through the member 1 will result, as illustrated in Figures 3 and 5.

At suitably spaced intervals along the length of the supporting member 1 transverse grooves or passages 6 are provided which communicate with the passages 4 and 5 internally of the member 1, and arranged alternately on each side of the metal strip 3 therethrough, to accommodate cross arms 7 at whose outer ends are secured the upper ends of arcuate sections of tubing or sheaths 8 being opposingly arranged and which curve downwardly meeting at their opposite ends and terminating within one of the passages 4 or 5, provided by the grooves 2, as illustrated in Figure 2. The sheaths 8 are secured to the cross arms 7 at *a* and to each other at *b* by welding, or similar device.

Through each of the sheaths 8 are slidably arranged stays 9 comprised of lengths of flexible steel wire of medium gage and which are securely attached at their inner ends at *c* within one of the passages 4 or 5, as illustrated in Figure 2. The sheaths 8, as previously stated, curve downwardly from the outer ends of the arms 7 and enter the member 1 in an arcuate course through passages 10 which communicate with the passages 4 and 5 in the same manner as do the passages 6 through which the arm 7 is arranged.

As illustrated in Figure 1, it is apparent that several of the assemblies just described are arranged laterally through the member 1 although the arms 7 and the sheaths 8 graduate in length from the top to the bottom of the device and each of the assemblies are positioned so that the arcuate sheaths 8 extend downwardly with exception to the lowermost of these members which curve upwardly from the lowermost arm 7 but terminate within one of the passages 4 or 5 in the same manner as the others of these members.

Secured to the outer ends of the stays 9 substantially T-shaped connections 11 slidably receive vertically disposed frame members 12, comprising lengths of flexible steel wire, which freely operate through bores 13 arranged through vertically disposed integral cylindrical portions of the connections 11, as illustrated particularly in Figure 4. Between the two lowermost arms 7 and between the outer ends of the lengths of wire 50

supported by these members are provided lengths of tubing 14 through which the lowermost ends of the vertically arranged lengths of wire or frame members 12 slidably operate. The lengths of tubing 14 are engaged at their uppermost ends and near their lowermost ends by connections 15 which are similar in construction to the members 11, previously described.

The lowermost members 15 also slidably engage the tubing 14 although the uppermost of the members 15 are rigidly secured to the uppermost ends of the sections of tubing 14 so that the latter are immovable with respect to these members. A ball joint connection 16, or similar device, is provided between the uppermost ends of the vertically arranged wire frame members 12 and the stays 9 projecting from the ends of the uppermost of the arcuate sheaths 8, as illustrated in Figure 1. The device is provided at its uppermost end with downwardly inclined brackets 17 arranged on each side of the member 1 suitably supporting the shoulders of the garment arranged on the device. A conventional hanger hook 18, also secured to the uppermost end of the member 1, provides means for suspending the apparatus in the drying room.

In operation, a garment, such as a lady's dress, when the same has been washed or otherwise subjected to a cleaning process, is arranged upon the invention and the vertical frame members 12 are urged inwardly or outwardly to properly conform to the contour of the garment, the proper size of the latter having been previously determined, and the dress suspended in the drying room. After the necessary adjustments have been accomplished the garment will dry in its proper form and the necessity for pressing the same is usually eliminated except for the touching up with an iron of the trim.

Obviously, by reason of the arcuately curved sheaths 8, the wire stays 9 slidably arranged therethrough, by reason of their resiliency, frictionally engage the inner walls of the sheaths 8 and remain in adjusted position, it being necessary only to urge the wire stays 9 inwardly or outwardly to the proper adjustments which will remain fixed on each side of the device until manually operated to a different position. The tendency of the highly resilient wire stays 9 is that of straightening out after the same have been flexed and consequently the greatest tension is exerted at the ends of the sheaths 8, thus the wire stays 9 maintain their fixed positions to which they are manually operated as described.

Since the free ends of the wire stays 9 are secured together at c it is necessary only to manually manipulate the connections 11, 15 and 16 on one side of the invention in order to attain uniformity and cause the device to assume the proper form. For example, when the connection 11 at the waistline is manipulated inwardly or outwardly the opposite wire stay 9 is also manipulated in the same manner moving the same distance toward or away from the member 1 and flexing the wire frame member 12 to assume the same form or degree of curve as that of the opposite wire frame member 12, the lower ends of these members slidably extending into the lengths of tubing 14 at the lower end of the device providing a uniformly flexible assembly affording the minutest adjustments conforming to the size and general shape of any garment fitted thereon.

Although the invention has been described with

great particularity, certain changes and modifications may be resorted to from time to time by those skilled in the art and such changes and modifications as may be considered within the spirit and intent of the invention may also be considered as falling within the scope of the appended claims.

What is claimed is:

1. A garment blocking and forming device comprising a central body member, a flexible frame adjustably supported by the said body member, flexible stays slidably connected to the said frame at spaced intervals along each side of the said body member and received within the same, tubular means encasing the said flexible stays and frictionally retaining the said frame in variable symmetrical forms.

2. In a garment forming and blocking apparatus, a central body member, a flexible frame supported by the said body member and symmetrically conformable therewith, flexible stays slidably engaging the said frame at their outer ends, curved sheaths entering the said body member at their inner ends and slidably receiving the said stays, the said sheaths being spaced along each side of the said body member and frictionally retaining the said arms in variable fixed positions.

3. A garment forming and blocking device comprising a central support, a flexible frame arranged longitudinally of the said support, arcuate sheaths spaced along and extending from each side of the said support, flexible stays slidably connected at their outer ends to the said frame and adapted to slidably enter the said sheaths at their opposite ends, the said sheaths frictionally retaining the said stays in fixed position whereby the said frame is uniformly flexed to and frictionally retained in a symmetrical shape.

4. A garment forming and blocking device comprising a central support, a flexible frame arranged longitudinally of the said support, curved tubular sheaths extending from the said support, flexible stays slidably connected at their outer ends to the said frame and slidably received by the said sheaths at their opposite ends, the said sheaths frictionally and adjustably retaining the said stays in fixed position.

5. A garment forming and blocking apparatus comprising a central rigid support, a multiple of curved tubular sheaths connected in the said support, a multiple of paired flexed stays of a flexible material slidably received by the said sheaths and partially embraced thereby, a flexible frame adjustably supported by the said stays, means secured to the outer ends of the said stays slidably engaging the said frame and friction means retaining the said stays in adjusted positions.

6. In a garment blocking and forming device comprising a central body member and a flexible wire frame supported by the said body member, arcuate tubular supporting sheaths opposingly arranged on each side of the said body member and extending thereinto, paired flexible stays having their outer ends slidably connected to the said frame and received by the said sheaths and having their inner ends connected, the said stays adapted to be flexed and retained in fixed positions within the said sheaths.

7. In a garment forming and blocking device having a central body member, the said body member having vertical passages therein, arcuate tubular sheaths spaced along each side of the

said body member and having their inner ends extending into the said passages therein a series of paired wire stays received by the said sheaths and connected at their inner ends, a flexible wire frame slidably supported at the outer ends of the said stays whereby the contour of the said frame is symmetrically varied by the longitudinal movement of the said stays.

5. 8. In a garment blocking and forming device, a central body member having longitudinal passages therein, a flexible frame, arcuately formed tubular sheaths opposingly arranged in pairs and

having their inner ends merging within the said passages and supported by the said body member, flexible stays adjustably received by the said sheaths and extending into the said passages, 5 slidable connections between the outer ends of the said stays and the said frame providing adjustable supports for the said frame and means frictionally retaining the said stays in adjusted position.
